UNITED STATES PATENT OFFICE.

GEORGE VAUGHN FLETCHER, OF MINNEAPOLIS, MINNESOTA.

OIL BURNER.

Application filed July 23, 1926. Serial No. 124,436.

My invention relates to oil burners of the type wherein the atomization of oil is produced by the action of air under violent agitation, as distinguished from oil burners wherein the atomization is produced mechanically by the action of a rotary cup, sprayer head or the like, driven at high velocity.

The major objects of the invention are simplicity of construction and relatively low cost of production, a minimum of power-driven elements or running parts, and, at the same time, the most complete combustion and highest possible heating efficiency.

15 A commercial form of the burner is illustrated in the accompanying drawings, where-in like characters indicate like parts throughout the several views.

Referring to the drawings:

20 Fig. 1 is a vertical section of the burner, showing the same applied to a boiler or furnace, some parts being broken away, some parts being shown in full, and some parts being sectioned on the line 1—1 of Fig. 2;

25 Fig. 2 is a plan view of the burner, some parts sectioned on the line 2—2 of Fig. 1, and some parts being broken away;

Fig. 3 is a side elevation of the burner, some parts being broken away;

30 Fig. 4 is an enlarged section taken on the line 4—4 of Fig. 1; and Fig. 5 is a fragmentary section on the line 5—5 of Fig. 2.

In Fig. 1, the numeral 5 indicates a boiler or furnace having the customary ash pit 35 6, but provided with an annular supporting plate 7 substituted for the grate and covered with an insulating material 8, such as concrete. In the preferred manner of installing the burner, the plate 7 and insulation 8 closely surround the upper portion of a large

40 cup-like air trunk 9 into one side of which air is blown through an air intake pipe 10 that is connected to the discharge spout 11 of a power-driven fan or blower 12. The case 45 of this blower 12 is mounted on a base 13, which is preferably a cast structure provided outside of the furnace with a laterally extended ground-engaging portion 14. Preferably, the rotary head of the blower 12 is

50 driven from a small electric motor 15 supported on the base 13. The inner end portion of the base 13 is adjustably supported by a screw-threaded leg 16 and the air trunk 9 is adjustably supported on the inner portion 55 of said base by screw-threaded supporting legs 17, which adjustable features make it

an easy matter to set the air trunk 9 and the bowl supported thereby and presently to be described in a true level position and at the proper altitude.

60 The numeral 18 indicates a combustion bowl, preferably a cast structure having an outstanding rim flange 19 that rests on the upper edge of the air trunk 9, forming a close joint therewith. Also, the bowl, immediately adjacent its supporting flange 19, has a short cylindrical portion 20 that telescopes into the air trunk 9 and keeps the lower portion of the bowl concentrically spaced from the walls thereof, so that the 65 air in the trunk can sweep completely around the bowl below said cylindrical portion 20.

70 At a plurality of points, as shown at four points circumferentially spaced, the bowl 18 is formed with air intake ports 21 and 21^a. 75 The port 21^a has considerable length circumferentially of the bowl and will direct the air delivered therethrough against the peripheral wall of the bowl, causing the same to directly take up a whirling motion 80 against the inner surface of the bowl. The oil or fluid fuel will be delivered into this port 21^a and, hence, the bottom of said port is inclined toward the interior of the bowl 85 so that surplus oil will not run out of the bowl. The ports 21, of which, as shown, there are three, open substantially tangentially into the bowl, but they are cut or formed so that they do not have the same 90 tendency to cause the air to hug the peripheral wall of the bowl, but rather tend to direct the air spirally inward and toward the axis of the bowl. The important action produced by these cross currents will be 95 further considered in the description of the operation.

100 The numeral 22 indicates a drain pipe or tube applied to the bottom and depending from the center of the bowl. The upper portion of the bowl is formed as a separate annular element 23 that is contracted. This portion 23 will be subjected to the most intense heat and, it being separately formed, may be made of carborundum or other material that is more highly refractory than 105 the cast body of the bowl. Even when the upper rim portion 23 of the bowl is of cast iron or steel, it should be formed separately from the bowl so that it may be readily replaced and so that it will better adapt 110 itself to uneven expansion and contraction. To concentrically hold the rim portion 23

to the body of the bowl, it is shown as rabbeted at its lower edge and made to loosely fit a correspondingly rabbeted portion of the bowl, as at 24.

5. In this preferred arrangement, the oil or fluid fuel is delivered to the air intake port 21^a through a pipe 25 that is extended through the side of the air trunk 9 and is tapped through the side of the bowl so that 10 it delivers the oil at the very top of said air port 21^a. The oil will thus be delivered to the port 21^a above the incoming blast of air and will be almost instantly vaporized, but any oil not instantly vaporized will 15 run down the inclined outer wall of said port 21^a and will all the while be subject to the whirling blast of air so that all of the oil will be vaporized before it reaches the bottom of the bowl. The supply of oil to 20 the pipe 25 may be regulated by a valve 26 and, of course, the oil supply may be from any suitable source, such as an elevated tank or pump, so far as this invention is concerned.

25. In connection with an oil burner of this character, a pilot light, such as a small gas flame maintained within the bowl for effecting initial combustion of the oil vapor, is desirable; and this pilot is preferably arranged as follows: A small gas pipe 27 is extended through and spaced from the walls of the drain pipe 22 and at its lower end is screwed into a coupling 28 shown as secured to and depending from the bottom of the 30 air trunk 9 by threaded engagement at 29. This coupling 28 has two compartments 30 and 31. The lower end of the gas pipe 27 leads upward from the compartment 30 and the lower end of the drain pipe 22 extends 35 downward into the open upper portion of the chamber 31 but is spaced from the walls of the latter so that said chamber 31 affords a drain from the bottom of the air trunk.

40. Elbows 32 and 33 are screwed into the coupling 28 and communicate, respectively, with the chambers 30 and 31. A gas supply pipe 34 leads to the elbow 32 and a drain pipe 35 leads from the elbow 33 to a suitable point of discharge. A pilot head 36 is applied to the upper end of the gas pipe 27, as shown, by threaded engagement, and is provided with a plurality of downwardly sloping gas discharge passages 37 that directs the plurality of pilot flames onto or 45 immediately above the bottom of the bowl.

Summary of operation.

When the blower is in action, air pressure 50 will be produced in the air trunk 9 and air from said trunk will be discharged into the bowl through the several tangential air ports 21-21^a. The several streams of air thus delivered into the bowl will set up a violent whirling or cyclonic action within 55 the bowl and the air in the air trunk sur-

rounding the bowl will also be caused to whirl to some extent thereby insuring an even supply of air through the several air ports.

The oil delivered into the bowl from the 70 fuel pipe 25 will be primarily taken up by the air introduced into the bowl through the port 21^a. The air introduced into the bowl through the port 21^a will be directed against the wall of the bowl and, under the action 75 of centrifugal force, will tend to hug the wall of the bowl and revolve therein with an upward spiral trend. The air delivered into the bowl through the several ports 21 will also be given a spiral rotary movement with- 80 in the bowl, but the air currents thus introduced will have a trend toward the axis of the bowl, so that they will cut through the whirling oil-laden air blast introduced through the port 21^a. These cross currents 85 or currents having the greater inward trend break up or tend to break up the primary spiral oil-laden current, thereby producing a thorough intermingling of the several currents and a turbulence of air currents that 90 insures the most complete atomization of the oil and most thorough commingling of the oil and air. Moreover, the inward trend of the disrupted cross currents introduced through the ports 21 very greatly improves 95 the action of the burner, not only generally but particularly at the center of the bowl, where there will be a tendency to more or less incomplete combustion, resulting in 100 some ultimate accumulation of carbon at the center of the bowl, whereas, with the arrangement described, such incomplete combustion and accumulation of carbon is eliminated.

Of course, centrifugal force will keep a 105 greater part of the whirling oil-vapor-laden air whirling against or close to the wall of the bowl so that the ultimate upward discharge thereof from the bowl will be retarded by the contraction of the rim portion of the bowl long enough to cause a most complete vaporization of the oil. The combustion will be started within the bowl, but the flame and the complete combustion will take place above and outside of the bowl. Centrifugal force, acting on the whirling vapor-laden air, will cause an expansion of the flame into a cup-shaped or saucer-shaped flame immediately upon its discharge or release from the rim of the bowl, with the result that the flame produced will be properly spread for the most complete combustion and most effective heat production.

It will be noted that the pilot throws a 125 plurality of flames radially outward from the center of the bowl and that the commingled air and oil are caused to whirl around the pilot in such manner that quick ignition is insured and there is a minimum of tendency to blow out the pilot flames.

When the burner is in action, the air laden with oil or vapor in the proper mixture for combustion will, as already indicated, be discharged from the top of the bowl in an annular out-spreading blast. Tests have shown that, at such time, there will be a flow of hot air from the combustion chamber axially downward into the bowl. This downward flowing stream of hot air, upon entering the bowl, is also caused to rotate and, as it spreads, will commingle with or act upon the vaporized oil and further assist in the final and more complete atomization thereof, so that the oil vapors will reach the flashing point as they are discharged from the bowl.

The efficiency of this comparatively simple burner has been thoroughly demonstrated in practice and the statements herein made are based on actual experience and tests in the use of the burner.

What I claim is:

1. In an oil burner, a combustion bowl having a plurality of peripheral circumferentially spaced air intake ports, means for introducing air into said bowl through said ports, thereby setting up a whirling motion of the air within the bowl, and oil delivery means opening directly into at least one of said ports that is located between certain other of the air ports, into which latter oil is not delivered.

2. The structure defined in claim 1 in which the air port into which oil is delivered has a bottom that inclines toward the interior of the bowl.

3. An oil burner comprising a cup-like air trunk, a blower connected to said air trunk, a bowl detachably mounted on the rim of said air trunk and depending thereinto but spaced from the sides and bottom thereof, said bowl having peripheral air intake means for delivering air from said trunk into said bowl and setting up a whirling motion of the air in the bowl, and a separately formed rim portion detachably mounted on said bowl.

4. The structure defined in claim 3 in which said detachable rim portion is contracted toward its upper edge.

5. In an oil burner, the combination with a bowl having a plurality of peripheral circumferentially spaced air intake ports, means for introducing air into the bowl through said ports, thereby setting up a whirling motion of the air within the bowl,

and an oil delivery port opening directly into the upper portion of at least one of said air intake ports.

6. The structure defined in claim 5 in which said bowl has a wall portion below the oil intake port and over which the oil will run from said port toward the bottom of the bowl while it is being acted upon by the whirling air.

7. In an oil burner an air trunk, means for delivering air into said trunk, a bowl set into said trunk and having peripheral air intake ports for delivering air from said trunk into said bowl and causing the same to whirl within the bowl, means for delivering oil into said bowl, whereby it will be taken up and vaporized by the air whirling within the bowl, a two-compartment coupling applied to the bottom of said air trunk and formed with gas and oil chambers, the latter opening into the bottom of said trunk, a gas supply pipe leading to said gas chamber, a gas pipe extended upward from said gas chamber and provided with a delivery head located within the bowl, a drain pipe surrounding said gas pipe and extended from the bottom of the bowl into the oil chamber of said coupling, and a drain pipe extended from said oil chamber.

8. In an oil burner, a combustion bowl having a plurality of peripheral air intake ports, at least one thereof being arranged to introduce the air substantially tangentially and at least one of said ports being arranged to introduce air into the bowl through the whirling air current first noted and with a greater trend toward the axis of the bowl, and means for introducing oil into the bowl where it will be taken up and vaporized by the whirling air within the bowl.

9. In an oil burner, a combustion bowl having a plurality of peripheral air intake ports, at least one thereof being arranged to introduce the air substantially tangentially and at least one of said ports being arranged to introduce air into the bowl through the whirling air current first noted and with a greater trend toward the axis of the bowl, and means for introducing oil into said bowl at the first noted air intake port.

In testimony whereof I affix my signature:

GEORGE VAUGHN FLETCHER.
